UNITED STATES PATENT OFFICE.

ELI J. BLAKE, OF BUFFALO, NEW YORK, ASSIGNOR, BY MESNE ASSIGNMENTS, TO GOULD CAR LIGHTING CORPORATION, OF NEW YORK, N. Y., A CORPORATION OF MARYLAND.

ELECTRICAL REGULATING APPARATUS.

Application filed January 3, 1923. Serial No. 610,419.

My invention relates to improvements in electrical regulating apparatus and more particularly to regulating apparatus for electrical generators driven at variable speed as from the axle of a railway car for supplying a storage battery and electric lights or other energy consuming devices. The main object of the invention is to provide an arrangement which is not only simple and efficient in operation but also one which is reliable and not likely to get out of order. Further and more specific objects, features and advantages will more clearly appear from the detail description given below taken in connection with the accompanying drawings which form a part of this specification.

In the drawings, Fig. 1 is a face view of a panel on which is located regulating apparatus adapted for carrying out the invention in a preferred form thereof. Fig. 2 is a side view of the same. Fig. 3 is a view similar to Fig. 1 but largely diagrammatic in order to show the various circuit connections. Fig. 4 is a plan view of the generator regulator carbon piles of Figs. 1, 2 and 3. Fig. 5 is an end view partly in section of variable resistance shown in Fig. 4.

Referring to Fig. 3, 1 represents a generator driven at variable speed as from the axle of a railway car and 2 a shunt field therefor. 3 and 4 represent pole pieces of an electro-magnet pivoted between which at 5 is an armature 6 having a pin 7 adapted to bear against the lower end of a lever 8 pivoted at 9; the upper end of which actuates a cross piece 10 and plungers 11 and 12 bearing against one end respectively of carbon piles 13 and 14. A spring 128 (shown in Fig. 1) tends to draw the armature 6 out of alignment with the pole pieces, and acts through the lever 8 to compress the carbon pile. 15 and 16 represent pole pieces of an electro-magnet between which pole pieces is pivoted at 17, armature 18 having a pin 19 bearing against the lower end of a lever 20 pivoted at 21, the upper end of which lever is adapted to operate a cross piece 22 and plungers 23 and 24 operating on the other end of carbon piles 13 and 14 respectively. A spring 130 (shown in Figs. 1 and 2) tends to retract the armature and compress the piles.

25 represents an armature pivoted at 26

between the pole pieces 4 and 16 having pivoted thereto at 27, a link 28 pivoted at its lower end to a switch member 29 adapted to close the circuit between fixed contacts 30 and 31. A spring 129 (shown in Fig. 1) tends to retract the armature and open the switch. 32 represents a storage battery adapted to be charged by the generator 1 and to supply lamps or other work circuit devices 33 when the generator is not running or is not running at sufficient speed to supply the necessary voltage for the same. 34 represents another variable resistance carbon pile in series between the storage battery 32 and lamps 33, and adapted to be actuated by plunger 35 operated by lever 36 pivoted at its upper end to the frame at 37 and carrying at its lower end a roller 38 adapted to be actuated by a cam 39 fixed on an armature 40, pivoted at its center to the frame between pole pieces 41 and 42 of an electro-magnet. A spring 161 (shown in Fig. 1) tends to retract the armature and compress the pile. 43 represents a switch adapted to connect electrical contacts 44 and 45, the switch being actuated by an armature 46 and electro-magnet 47. In the diagrammatic showing the core 46 has a pin 48 operating in a slot in the switch 43 which is pivoted at 49 so that when the solenoid 47 attracts core 46, the switch member 43 is pulled up to electrically connect contacts 44 and 45.

As shown in Fig. 3 the main circuit from the generator leads from the positive pole through conductor 50 to binding post 51, thence through conductor 52 and an electromagnetic coil 53 adjacent the pole piece 16, then through conductor 54 and binding post 55, thence through conductor 56 and binding post 57, thence through conductor 58 to the battery 32 and conductor 59 to the lamps 33. From the opposite terminal of the lamp or work circuit, the main current passes through conductor 60 and binding post 61, thence through the carbon pile 34 and conductor 62, binding post 63, thence through conductor 64, binding post 65 through switch member or contact piece 66 and conductors 67 and 68, binding post 69, through switch contact 30, switch 29, switch contact 31 to binding post 70, thence through main fuse 71 and conductor 72 to the negative side of the generator 1. The

main current from the battery returns through conductor 73, binding post 74, thence through conductor 75, binding post 76, thence through conductor 77 and electro-magnet coil 78 on the magnet adjacent pole piece 3, thence through conductor 79, binding post 80 and then through conductors 81 and 68 and back to the negative terminal of the generator. 82 represents an electro-magnetic coil on the magnet adjacent pole piece 15 which electro-magnetic coil 82 may be connected in the lamp circuit or branch by swinging contact 66 away from contact 85 and causing it to connect contacts 65 and 84. The current from the lamps then passes from contact 65 to contact 84, then through conductor 86, coil 82, conductor 87 to the binding post 85 and thence through conductors 67 and 68 back to the negative side of the generator.

The carbon pile 34 with its operative parts serves as a lamp regulator to maintain substantially constant voltage on the lamps irrespective of the voltage applied to the battery. For this purpose electro-magnetic coils 88 and 89 which energize the electro-magnet operating the armature 40, are connected in series with one another and also across the lamp circuit through a ballast resistance 90, the circuit being from the positive side of the lamp circuit through conductors 59, 58, conductor 91 and binding post 92, thence through conductors 93, electro-magnetic coil 88, conductor 94, electro-magnetic coil 89, conductor 95, ballast resistance 90, conductor 96 and binding post 97, thence through conductor 98 to binding post 61 and through conductor 60 to the opposite side of the lamp circuit. If there tends to be an increase in voltage applied to the lamp circuit due to an increase in voltage applied across the battery, then the electro-magnetic coils 88 and 89 so attract the armature 40 through pole pieces 41 and 42 that the cam member 39 backs away from the roller 38 on lever 36 thereby decreasing the pressure exerted thereby on the carbon pile 34 so as to increase the drop in voltage between battery and lamps and maintain the voltage on the lamps substantially constant. Any tendency to a decrease in voltage across the lamps causes an opposite effect.

The carbon piles 13 and 14 are connected in series with one another and in series with the shunt field 2 across the generator, the circuit being as follows—from the positive side of the generator through shunt field 2, binding post 99 through conductor 100, binding post 101, thence through conductor 102, carbon pile 14, thence through conductor 103, and carbon pile 13, thence through conductor 104, fuse 105, conductor 106, main fuse 71 and conductor 72 to the opposite side of the generator. 107 represents

a voltage coil connected across the generator and battery through a ballast resistance 108^a, the circuit being as follows—from the positive side of the generator through conductor 50, binding post 51, conductor 52, coil 53, conductor 54, binding post 55, conductor 108, binding post 109, electro-magnetic coil 107, binding post 110, conductor 111, binding post 112, ballast resistance 108^a, binding post 113, conductor 114, back to conductor 72 on the negative side of the generator. The positive connection for the voltage coil 107 is made at the binding post 55, adjacent to the battery connection rather than at binding post 51, adjacent to the generator in order that the voltage coil may control in accordance with the output voltage to the battery, irrespective of the drop of potential in the current coil 53.

In operation when the generator attains a critical predetermined speed and the voltage of the generator accordingly attains a predetermined value, the voltage coil 107 will become of sufficient strength to cause the armature 25 to be attracted by pole piece 4 and so close the switch 29 between contacts 30 and 31 and thus close the circuit from the generator to the storage battery and lamps. If as the speed of the generator increases the current supplied by the generator should tend to become greater than that desired, the strength of coil 53 will be such as to attract the armature 18 and thus move pin 19 away from lever 20 and so relieve the pressure exerted thereby on the right-hand ends of carbon piles 13 and 14 as viewed in Fig. 3 and thus weaken the field of the generator and so maintain the voltage of the generator at such a value as to maintain substantially constant current output of the generator. If it is desired to maintain substantially constant battery current irrespective of the amount of the current taken by the lamp or work circuit, then the switch contact 66 is moved to connect contacts 65 and 84 so that the current returning from the lamps passes through electro-magnet coil 82 which is wound on the magnetic frame so as to oppose coil 53 so that the net result is a regulation of the generator to maintain substantially constant battery current.

When the battery becomes substantially charged as indicated by a predetermined rise in voltage across its terminals, the strength of voltage coil 107 becomes sufficient to cause the armature 6 to be attracted by pole pieces 3 and 4 thereby moving pin 7 away from lever 8 and releasing the pressure exerted thereby on the left hand end of carbon piles 13 and 14 as viewed in Fig. 3, so regulating the field strength of the generator as to maintain voltage thereof substantially constant. This tends to produce a gradual tapering off of the battery current as its back

pressure increases and hence a weakening of electromagnetic coil 53 whereby the armature 18 returns to its position under the action of resilient means hereafter to be described. In order that this dropping off of the battery current may be more rapidly effected after the battery has become substantially charged, the coil 78 is placed on the electro-magnet embodying pole pieces 3 and 4 and is connected in the battery branch and therefore, is responsive to decreases in the battery circuit. It is wound to oppose the electro-magnetic coil 107 whereby a decrease in the battery current through electro-magnet 78 increases the effective strength of magnet coil 107 on the armature 6 and so causes the same to regulate the generator to maintain a gradually decreasing voltage output which causes a more rapid tapering off of the battery charging current at this stage.

When the generator is not running or is running below critical speed and the main switch 29 is open and the storage battery 32 is supplying the lamps 33, the solenoid 47 acts upon core 46 to close switch 43 to connect contacts 44 and 45, thus placing a shunt circuit around the carbon pile 34 through conductor 98, the switch 43 and conductor 62, in order that the voltage drop between the battery 32 and lamp circuit 33 may be reduced to a minimum. This is effected through the action of the main switch. One side of the solenoid 47 is connected to contact 69 of the main switch through conductor 115, conductor 116, binding post 74, conductor 75, binding post 76, conductor 77, coil 78, conductor 79, binding post 80, conductor 81 and conductor 68. The other side of the solenoid 47 is connected to the other main switch contact through conductor 117, conductor 114, fuse 71 and binding post 70. When the main switch 29 is open some current will pass from the battery back through the generator and through coil 47 and thus energize solenoid 47 and cause it to close switch 43 and thus shunt out the carbon pile variable resistance 34. When the main switch 29 is closed the solenoid 47 is substantially short-circuited so that the switch 43 is opened thereby placing the carbon pile 34 in series between the battery and lamps. When certain types of storage batteries are used as for example, the so-called Edison battery, it may be desirable to place a further ballast resistance in series with the voltage regulating coil 107 and for this purpose an additional resistance 118 is provided connected between binding posts 112 and 119. When it is desired to include this resistance in series with the ballast resistance 108, the conductor 120, one end of which is connected to the ballast resistance 108, is switched from binding post 112 to binding post 119.

As shown in Figs. 1 and 2 the main switch 65 comprises leaf spring contacts 30 and 31 suitably secured to base piece 164 of insulating material which in turn is secured to the base panel 121. These contacts are beveled at their outer end and switch member 29 is bent to conform therewith and secured to a member 122 pivoted at its inner end by a knife edge member 165 bearing on the base piece 164 and adapted to be pulled upwardly by the link 28 attached to the armature 25 when the armature is attracted by its magnet. A spring 123 tends to maintain the link in position on the pin 124 on member 122 and pin 27 on the armature, and to hold the knife edge 165 against its seat.

The electro-magnet coils 78, 107, 53 and 82 are shown as mounted on the magnetic frame 125 secured to the base plate 121 by screws 126. The respective pole pieces 3, 4, 16 and 15 extend outwardly and co-axially from the respective electro-magnetic coils as shown in Figs. 1 and 2 so as to provide ample space for the armatures 6, 25 and 18 to swing therebetween, these armatures being pivoted on pivots carried by the frame 125. The outer ends of each are held in place by non-magnetic frame piece 127 extending across the front of the magnets. Armatures 6, 25 and 18 are normally swung away and out of line with their respective pole pieces by springs 128, 129 and 130 respectively, the upper ends of which springs are held in place by hooks 131, adjustably screwed into a frame plate 132, carried by posts 133 supported on a frame piece 134, secured to the frame 125 by means of screws 135. The lower ends of the springs 128, 129, and 130 are connected with links 154, 155 and 156, the lower ends of which are pivotally connected with pins 157, 158 and 159 respectively, which pins are rigid with the armatures 6, 25 and 18 respectively and extend up through holes 160, 161 and 162 respectively in the outer frame plate 127. The springs 128, 129 and 130, therefore, normally pull the armatures away from and out of line with their respective pole pieces until the pins 157, 158 and 159 engage the edges of the openings 160, 161 and 162 respectively, which serve as stops for the same. That is, the edges of these apertures 160, 161 and 162 serve to limit the movement of the armatures in both directions. The levers 8 and 20 are pivoted to the frame piece 134, the same being bent or shaped as shown in Fig. 2 in order that the lower arms thereof may engage the rollers or pins 7 and 19 respectively, while the upper ends thereof may operate upon the carbon piles 13 and 14.

The carbon piles 13 and 14 are contained in insulating cylinders 136 and 137 respectively, which cylinders are closed by cap pieces 138 (see also Fig. 4). In practice I prefer to make the cylinders of steel tubes coated with vitreous insulating enamel. The

plungers 11, 12, 23 and 24 are adapted to slide through these cap plates and operate on the ends of the carbon piles respectively through electrically conducting heads 139 attached to the inner ends thereof. The plungers 11 and 12 are connected together by the member 10, the ends of which fit in slots in nuts 140 secured on the plungers 11 and 12 respectively, and the cross-connecting member 10 is provided with two buttons 141 against which the upper end of the lever 8 is adapted to bear, the upper end of lever 8 being relatively wide for this purpose. The plungers 23 and 24 are operatively connected together by a lever member 22 by reason of the ends of the member 22 being forked and bearing against pins 141^a extending through the members 23 and 24 respectively. The member 22 is held to bear against the pins 141 by means of nuts 142 screwed on to the plungers 23 and 24 respectively and bearing against a leaf spring 143 secured to the member 22. The upper end of the lever 20 bears against the member 22 at a single point 144. The members 10 and 22 are pressed outwardly toward the levers 8 and 20 respectively by means of coil springs 145 and 146 respectively. The cylinders 136 and 137 containing the carbon piles are clamped together by two pairs of clamping bands 151 secured to each other and to the spacing blocks 149 at their centers by tubular rivets 166, and secured to each other at their ends by rivets 152. Leaf springs 147, 148 secured by screws 150 to the spacing blocks 149 serve to retain the cap pieces 138 in the ends of the cylinders. The parts shown in Fig. 4 thus constitute an assembled unit which is removable from the regulator for renewal or maintenance. Enlarged heads on the lower ends of the rivets 152 serve as feet for the assembled unit and rest on bosses formed on the frame member 134. Studs 153 projecting upward from the frame member through the tubular rivets 166 serve to locate the assembled unit, and wing nuts 167 screwed on the studs retain it in place.

The pole pieces 3, 4, 16 and 15 are cut away as shown at 154 to accommodate the ends of the armatures and permit the armatures to swing about their pivots between the pole pieces. The armatures 6 and 18 are provided with copper damping bands 155 in order to damp out oscillations of the armatures as far as practicable.

The ballast resistances 90 and 108^a are tubular enameled resistance units. At the right hand end in Fig. 1 they abut against a bracket 157 which is provided with bosses to locate them. At the left hand end they abut against suitably formed heads on plungers 168 which are forced inward to retain the resistance units by compression springs 158. The plungers 168 slide in open-

ings formed in the bracket 169 which is attached to the base plate 121.

The lamp regulator carbon pile 34 is supported on suitable insulating bars 159 and is provided with a fixed adjustable abutment 160 at one end. A coiled tension spring 161 has one end secured to the lamp regulator frame by hook 162 and its other end connected with the armature 40 by link 163, whereby when the voltage applied to the work circuit exceeds a predetermined value necessary to overcome the tension of spring 161, the armature 40 is given a slight rotation and so permits the lever 36 to decrease the pressure exerted on the pile 34. 80

It will be noted that the magnet coils 78, 107, 53 and 82 are all wound on separate legs of the magnetic structure whereby the coils are similar in diameter and the arrangement is better adapted to act upon the torsion armatures pivoted between the respective pole pieces. When the current coil 53 is acting to regulate the carbon piles 13 and 14, by varying the pressure through the plungers 23 and 24, the opposite ends of the piles remain substantially stationary due to the fact that the spring 128 holds the armature 6 in its off position, the voltage being insufficient to cause it to overcome the tension of spring 128. Likewise during the period when the voltage coil 107 is acting to regulate the carbon piles 13 and 14 through the plungers 11 and 12, the opposite ends of the piles 13 and 14 at plungers 23 and 24, remain substantially stationary. 90 The tubes 136 and 137, together with the straps 151 form suitable supporting means for the carbon piles 13 and 14 which are removable therewith by merely unscrewing the wing nuts 167. These carbon piles are 100 removable from the rest of the parts without any disconnection from the levers 8 and 20 since the levers are not connected with the piles or the plungers operating the same except by bearing against the plungers or 110 the parts connecting the plungers. That is, each of the levers has one end bearing on the plungers but is otherwise disconnected and free therefrom so that these carbon piles with their supporting means may be removed without any disconnection from the piles or said levers. Likewise the levers 8 and 20 are easily removed from the electromagnets and their armatures because the levers are not positively connected therewith but merely have a bearing engagement with the operating pins on the armatures, the armature pins being maintained in engagement with the levers by the springs 128, etc. 115 The springs 145 and 146 act to press the cross members 10 and 22 with the plungers away from the piles and toward the levers respectively to maintain the same in engagement with the upper ends of the levers 8 and 21 respectively. The lever 8 acts 120 125 130

- against the spaced apart bearing points 141 on cross member 10 and any unequal expansion between the piles 13 and 14 is taken care of by the oscillation of the cross member 5 22 at the opposite end which has pivotal connection with the plungers 23 and 24 and only one bearing point against the lever 20. When the system is being started up the main switch 29 is open but when the voltage 10 applied to the voltage coil 107 reaches a critical value, it acts upon the armature 25 to cause the main switch to be closed whereupon current is supplied through the coil 53 in a direction to aid coil 107 acting on 15 the armature 25 to maintain the main switch 29 closed. When the voltage of the generator drops below the value necessary to charge the battery or supply the lamps due to a decrease in the speed of the 20 generator, then current from the battery will flow back through coil 53 and through the generator in the opposite direction and so decrease the magnetic force acting on armature 25 as to promptly open the main 25 switch. By this arrangement it will be seen that the main switch is operated by the same coils which are used for controlling the carbon piles in series with the generator field.
- 30 When the armature 6 is held against its stop by the spring 128, it will require a certain potential applied to coil 107 to operate the armature to act on the carbon piles 35 13 and 14. The swing of the armature is so arranged that, after the armature has started to swing toward the pole pieces under such action of coil 107, a slightly less potential will be required to further move the armature 6 in line with its pole pieces.
- 40 That is, it will require a difference of some three or four volts to first start the armature 6 over the potential maintained throughout the remainder of the stroke although throughout substantially the whole 45 of the stroke, the potential actually required to move the armature remains substantially constant; this being accomplished by properly co-ordinating the effect of spring 128 with the effect of the electro-magnet on the 50 armature 6, at its different positions and the effect of any back pressure of the carbon pile so that as the turning moment applied to the armature increases as it approaches the line of the pole pieces with a given potential, the counter effect of the spring 128 similarly increases and this with any material increase in back pressure of the carbon pile, permits the constant potential required to maintain the armature 6 in any 55 position throughout the most of its movement. With this effect it may be unnecessary to use the coil 78.
- 60 Although I have described my improvements in great detail and with respect to a preferred form thereof, I do not desire 65 to be limited to such details or form since many changes and modifications may be made and the invention embodied in widely different forms without departing from the spirit and scope thereof in its broader aspect.
- What I claim as new and desire to secure by Letters Patent, is:
1. In an apparatus of the class described the combination of a compressible variable 75 resistance, a magnet having two pole pieces, an armature therefor pivotally mounted between said pole pieces, means whereby said armature acts to vary said resistance, a current coil energizing said magnet to cause the 80 armature to increase said resistance, and another current coil acting on said magnet to oppose the action of said first coil, said coils being wound on separate legs of said magnet. 85
  2. In an apparatus of the class described the combination of a compressible variable resistance for regulating the voltage of a generator, a magnet having two pole pieces, an armature therefor pivotally mounted between said pole pieces, means whereby said armature acts to vary said resistance, and a current coil and a voltage coil acting on 90 said magnet to control said armature to vary said resistance, said coils being wound on 95 separate legs of said magnet.
  3. Apparatus of the class described having in combination a carbon pile, a plunger operating on one end of the pile, a lever having one end bearing on said plunger, but otherwise not connected and, free therefrom, an electro-magnet and armature, said armature having a part bearing against said lever but otherwise disconnected and free therefrom, and resilient means operating to press said armature part against said lever and said lever against said plunger.
  4. Apparatus of the class described having in combination a plurality of carbon piles, plungers operating on opposite ends of each of said piles, a member connecting the plungers at one end, a member connecting the plungers at the other end, two levers operating on said members respectively and having a bearing engagement therewith but being otherwise not connected therewith, electro-magnets having armatures with parts bearing against said levers respectively but being otherwise disengaged therewith, and resilient means acting to maintain said armature parts in engagement with said levers and said levers in engagement with said members. 100
  5. Apparatus of the class described having in combination a plurality of carbon piles, plungers operating on opposite ends of each of said piles, a member connecting the plungers at one end, a member connecting the plungers at the other end, two levers operating on said members respectively and 105 having a bearing engagement therewith but being otherwise not connected therewith, electro-magnets having armatures with parts bearing against said levers respectively but being otherwise disengaged therewith, and resilient means acting to maintain said armature parts in engagement with said levers and said levers in engagement with said members. 110
  6. Apparatus of the class described having in combination a plurality of carbon piles, plungers operating on opposite ends of each of said piles, a member connecting the plungers at one end, a member connecting the plungers at the other end, two levers operating on said members respectively and having a bearing engagement therewith but being otherwise not connected therewith, electro-magnets having armatures with parts bearing against said levers respectively but being otherwise disengaged therewith, and resilient means acting to maintain said armature parts in engagement with said levers and said levers in engagement with said members. 115
  7. Apparatus of the class described having in combination a plurality of carbon piles, plungers operating on opposite ends of each of said piles, a member connecting the plungers at one end, a member connecting the plungers at the other end, two levers operating on said members respectively and having a bearing engagement therewith but being otherwise not connected therewith, electro-magnets having armatures with parts bearing against said levers respectively but being otherwise disengaged therewith, and resilient means acting to maintain said armature parts in engagement with said levers and said levers in engagement with said members. 120
  8. Apparatus of the class described having in combination a plurality of carbon piles, plungers operating on opposite ends of each of said piles, a member connecting the plungers at one end, a member connecting the plungers at the other end, two levers operating on said members respectively and having a bearing engagement therewith but being otherwise not connected therewith, electro-magnets having armatures with parts bearing against said levers respectively but being otherwise disengaged therewith, and resilient means acting to maintain said armature parts in engagement with said levers and said levers in engagement with said members. 125
  9. Apparatus of the class described having in combination a plurality of carbon piles, plungers operating on opposite ends of each of said piles, a member connecting the plungers at one end, a member connecting the plungers at the other end, two levers operating on said members respectively and having a bearing engagement therewith but being otherwise not connected therewith, electro-magnets having armatures with parts bearing against said levers respectively but being otherwise disengaged therewith, and resilient means acting to maintain said armature parts in engagement with said levers and said levers in engagement with said members. 130

having a bearing engagement therewith but being otherwise not connected therewith, electro-magnets having armatures with parts bearing against said levers respectively but being otherwise disengaged therewith, and resilient means acting to maintain said armature parts in engagement with said levers and said levers in engagement with said members, and resilient means 10 pressing said members and plungers away from said piles and toward said levers respectively.

6. An apparatus of the class described having in combination two carbon piles, a 15 plunger operating on each end of each pile, means connecting the plungers at one end, a lever having spaced apart bearing points on said means to operate said plungers simultaneously, electro-magnetic means controlling said lever, an equalizing member having a pivotal connection with each of the plungers at the opposite end, a lever having a single bearing point on said equalizing member to operate said last mentioned 20 plungers, and electro-magnetic means controlling the operation of said last mentioned lever.

7. An apparatus of the class described having in combination two carbon piles, 30 plungers operating on each end of each pile, means connecting the plungers at one end, a lever having spaced apart bearing points on said means to operate said plungers simultaneously, electro-magnetic means controlling said lever, an equalizing member having a pivotal connection with each of the plungers at the opposite end, a lever having a single bearing point on said equalizing member to operate said last mentioned 35 lever, and resilient means pressing the plungers and connecting means and equalizing lever away from the pile and toward 40 the levers respectively.

8. Apparatus of the class described having in combination a carbon pile, a plunger operating on the end of the pile, a lever operating on said plunger but being otherwise 50 not connected therewith, an electro-magnet having an armature with a part bearing against said lever but being otherwise disengaged therefrom, resilient means acting to maintain said armature part in engagement with said lever and said lever in engagement with said plunger, and resilient means pressing said plunger toward said lever and away from said carbon pile.

9. Apparatus of the class described having in combination, two carbon piles connected in series with one another, a lever operating on one end of both piles to vary the resistance thereof, an electro-magnet having two pole pieces, an armature therefor pivoted between said pole pieces, means

whereby said armature actuates said lever, a coil controlling the energization of said magnet, a lever operating on the other end of said piles, another electro-magnet having two pole pieces, an armature therefor pivoted between said last mentioned pole pieces and a coil controlling the energization of said last mentioned magnet to cause its armature to operate said second lever to vary the resistance of the pile independently of 75 said first lever and electro-magnet.

10. Apparatus of the class described having in combination a carbon pile, a lever operating on one end of the pile, a potential electro-magnet having two pole pieces an 80 armature therefor pivoted between said pole pieces and controlling the operation of said lever, a lever operating on the other end of said pile, a current electro-magnet having two pole pieces and an armature therefor pivoted between said pole pieces and controlling the operation of said second lever, one of said magnets with its cooperating armature and lever acting to vary the 85 resistance of the pile independently of the 90 other magnet and its cooperating armature and lever.

11. Apparatus of the class described having in combination, a carbon pile for regulating a generator field, a lever operating on one end of the pile, a potential electro-magnet having two pole pieces, an armature therefor pivoted between said pole pieces and controlling the operation on the other 95 end of said pile, a current electro-magnet having two pole pieces and an armature therefor pivoted between said pole pieces and controlling the operation of said second lever, one of said magnets with its cooperating armature and lever acting to vary the 100 resistance of the pile independently of the other magnet and its cooperating armature and lever, a switch, and an armature affected by both of said magnets for controlling 105 the operation of said switch. 110

12. Apparatus of the class described having in combination, a carbon pile, a lever operating on one end of the pile, a potential electro-magnet having two pole pieces an 115 armature therefor pivoted between said pole pieces and controlling the operation of said lever, a lever operating on the other end of said pile, a current electro-magnet having two pole pieces and an armature therefor pivoted between said pole pieces and controlling the operation of said second lever, each of said magnets with its cooperating armature and lever acting to vary the 120 resistance of the pile independently of the other magnet and its cooperating armature and lever.

13. Apparatus of the class described having in combination, a carbon pile, a lever operating on one end of the pile, a potential 125 electro-magnet having two pole pieces an 130

- armature therefor pivoted between said pole pieces and controlling the operation of said lever, a lever operating on the other end of said pile, a current electro-magnet having two pole pieces and an armature therefor pivoted between said pole pieces and controlling the operation of said second lever, one of said magnets with its cooperating armature and lever acting to vary the resistance of the pile independently of the other magnet and its cooperating armature and lever and each of said armatures having damping bands on each side of its pivot.
14. Apparatus of the class described having in combination a carbon pile for regulating a generator, a potential magnet having two pole pieces and an armature pivoted between said pole pieces, means whereby said armature acts to vary the resistance of said pile, a spring opposing the action of the magnet on the armature, and means whereby the movement of the armature by the spring away from said poles is limited, said spring being so connected with the armature and adjusted that a predetermined magneto-motive force applied to the potential magnet acts to substantially balance the spring throughout substantially the whole range of movement of the armature.
15. Apparatus of the class described having in combination a carbon pile for regulating a generator, an electro-magnet having two pole pieces and an armature pivoted between said pole pieces, means whereby said armature acts to vary the resistance of said pile, a spring opposing the action of the magnet on the armature, and means whereby the movement of the armature by the spring away from said poles is limited, said spring being so connected with the armature and adjusted that a predetermined magneto-motive force applied to the potential magnet acts to substantially balance the spring throughout substantially the whole range of movement of the armature.
16. Apparatus of the class described having in combination a carbon pile for regulating a generator, a potential magnet having two pole pieces and an armature pivoted between said pole pieces, means whereby said armature acts to vary the resistance of said pile, a spring opposing the action of the magnet on the armature, and means whereby the movement of the armature by the spring away from said poles is limited, said spring being so connected with the armature and adjusted that a predetermined magneto-motive force applied to the potential magnet acts to substantially balance the spring throughout substantially the whole range of movement of the armature.
17. Apparatus of the class described having in combination a carbon pile for regulating a generator, a potential magnet having two pole pieces, and an armature pivoted between said pole pieces means whereby said armature acts to vary the resistance of said pile, a spring opposing the action of the magnet on the armature, and means whereby the movement of the armature by the spring away from said poles is limited, said spring being so connected with the armature and adjusted that a predetermined magneto-motive force applied to the potential magnet acts to substantially balance the spring throughout substantially the whole range of movement of the armature.
18. Apparatus of the class described having in combination a carbon pile for regulating a generator, a potential magnet having two pole pieces and an armature pivoted between said pole pieces, means whereby said armature acts to vary the resistance of said pile, a spring opposing the action of the magnet on the armature, and means whereby the movement of the armature by the spring away from said poles is limited, said spring being so connected with the armature and adjusted that a predetermined magneto-motive force applied to the potential magnet acts to substantially balance the spring throughout substantially the whole range of movement of the armature.

In testimony whereof I have signed my name to this specification.

ELI J. BLAKE.
